FLARE PISTOL

Herbert E. Mills, Detroit, Mich., assignor to
 Eureka Vacuum Cleaner Company, Detroit,
 Mich., a corporation of Michigan

Application April 12, 1943, Serial No. 482,786

3 Claims. (Cl. 42—40)

This invention relates to pistols and has particular reference to that type which are sometimes designated as signal dischargers which are designed for shooting flares and the like.

Principal objects of the invention are:

To provide a pistol which is light in weight and dependable in operation;

To provide a pistol in which the parts thereof are made up out of steel and are formed by stamping operations;

To provide a pistol which is particularly adapted for production at comparatively low cost on a high production basis.

Other objects and advantages of the invention will be apparent from a consideration of the following specification taken in conjunction with the accompanying drawings, of which there are two sheets and wherein:

Fig. 1 is a side elevational view, partially broken away, of a pistol embodying the invention;

Fig. 2 is a front elevational view thereof;

Fig. 3 is a horizontal sectional view taken in a plane along the line 3—3 of Fig. 1;

Fig. 4 is an exploded view of the major parts of the pistol assembly exclusive of the firing and extractor mechanism thereof;

Fig. 5 is an elevational view of the handle, looking in the direction of the arrow B in Fig. 4;

Fig. 6 is an elevational view of the main frame, looking in the direction of the arrow C in Fig. 4.

As illustrated in Figs. 4, 5, and 6, the main parts of the pistol assembly comprise a handle 10, a main frame 12, and a barrel 14. The main frame 12 and handle 10 are joined together as illustrated in Figs. 1-3 and form a housing and support for the firing and extractor mechanism. The handle itself consists of a channel-shaped member having sides 16 connected by an integral flange or wall 18 which extends around approximately one-half of the periphery of the sides 16. In cross section the handle 10 is U-shaped as clearly illustrated in Fig. 3, and the open side of the handle 10 is closed by the main frame 12 which in cross section is also U-shaped as illustrated in Fig. 3.

The sides 20 of the main frame 12 throughout a portion of their length may be nested within the sides 16 of the handle 10 and suitably secured thereto in any desired manner. The main frame 12 is suitably curved so as to conform to the curvature of the edges of the sides 16 of the handle 10, and includes a forwardly extending portion 22 to which the barrel is secured as hereinafter explained. The main frame

12 further includes a pair of ears 24 which form a support and guide for one end of the hammer spring, and a pair of upwardly extending lugs 26 to which the firing pin housing 28 and breech-block 30 are secured as hereinafter set forth. The handle 10 and the main frame 12 may be formed of a single stamping or of a plurality of stampings which are integrally united so as to provide these parts in the form substantially as illustrated in Figs. 4, 5, and 6.

The forwardly extending portion 22 of the main frame includes upstanding flanges 32 having apertures 34 therein. Pin 36 extends through apertures 34 and forms a pivot for the barrel 14.

15 The barrel 14 is carried by a barrel carrier 37 which encircles the barrel and an inverted U-shaped hinge member comprising depending flanges 38 provides with apertures 40 through which the pivot pin 36 extends, the flanges 38 being positioned between the flanges 32 of the projection 22. The barrel is normally positioned as illustrated in Fig. 1 and locked in this position by a breech lock consisting of a lever 42, shoulders 44 of which engage shoulders formed by 20 the sides of a slot in the breechblock 30 through which the lever 42 extends for locking the barrel with its breech closed.

25 The firing pin housing 28 is suitably affixed to the back of the breechblock 30 and secured between the upwardly extending lugs 26 of the main frame by screws 46. The firing pin housing carries the firing pin 58 and positions the rear end of it for engagement by a hammer 48 pivoted on a pin 50 carried by the upwardly extending flanges 32 of the main frame. A guide pin 52 is pivoted to the hammer 48 and has its other end slidably in a guide 54 carried by the ears 24 of the main frame.

30 The guide 54 consists of a cross pin having a hole therein through which the pin 52 slides, and a spring 56 is confined between shoulders formed on one end of the pin 52 and the cross pin 54 for driving the hammer against the firing pin 58 after it has been retracted and released under the action of the trigger 60. Breechblock 30 closes the breech end of barrel 14 and is provided with a guide in which the firing pin 58 works, the front end of pin 58 being cooperable with a cartridge positioned in barrel for firing 35 such cartridge when the hammer strikes the end of pin 58.

35 The trigger 60 is pivotally mounted on a pin 62 carried by the side flanges 32 of the main frame, and a sear 64 is pivotally connected to the upper end of the trigger at 66. The turned-

up free end of the sear is engageable with the end 68 of the hammer 48 upon movement of the trigger in a clockwise direction about its pivot for retracting the hammer. Toward the end of the trigger's movement in a clockwise direction, a lug 70 on the hammer 48 engages the end of the sear and disengages the same from the element 68, thereby releasing the hammer 48 enabling it to strike the firing pin 58.

When the breech latch 42 is released the barrel 14 may be swung in a clockwise direction about its pivot 36 to open the breech. The extractor 80 is associated with the barrel and operable upon opening of the breech for extracting a cartridge shell from the barrel. The particular details of the extractor form no part of the present invention and hence need not be further described, but the extractor is disclosed and claimed in a co-pending application, Serial No. 447,292, filed June 16, 1942, by Glen R. Severance, Fred K. Comiskey, and Hilton E. Jones.

The sides 16 of the handle may have suitably affixed thereto pads 82 which make the handle easier to grasp in the hand.

While the invention has been described with some detail, it is to be understood that the description is for the purpose of illustration only and is not definitive of the limits of the inventive idea. The right is reserved to make such changes in the details of construction and arrangement of parts as will fall within the purview of the attached claims.

I claim:

1. A pistol including a handle, a main frame and a barrel, said handle comprising a channel shaped member having spaced and parallel side flanges, said main frame comprising a channel shaped member having spaced and parallel side flanges, the flanges of one of said members being received between the side flanges of the other of said members and cooperating therewith to define a housing for enclosing and supporting firing mechanism for the pistol, said main frame being formed with an upwardly extending portion and a forwardly extending portion projecting forwardly of said upwardly extending por-

tion, a breech block supported by said upwardly extending portion and said barrel being connected to and supported by said forwardly extending portion and having its breech end positioned in operative relationship with said breech block.

2. A pistol comprising a hollow handle and a barrel, said handle comprising a channel shaped member having spaced side flanges, a frame member received between the side flanges of said handle and cooperating therewith to complete the handle and define a housing for enclosing and supporting firing mechanism for the pistol, said frame member being formed with an upwardly extending portion and a forwardly extending portion projecting forwardly from the lower end of said upwardly extending portion, a breech block supported by said upwardly extending portion, said barrel being pivotally connected to and supported by said forwardly extending portion and adapted to have its breech end positioned in operative relationship with said breech block, and said firing mechanism including a trigger pivotally supported by said frame member.

3. A pistol comprising a handle, a main frame and a barrel, said handle comprising a channel shaped member having spaced side flanges, said main frame comprising a member received between the side flanges of said handle and cooperating therewith to define a housing for enclosing and supporting firing mechanism for the pistol, said main frame being formed with an upwardly extending portion and a forwardly extending channel shaped portion projecting forwardly of said upwardly extending portion, a breech block supported by said upwardly extending portion and a barrel carrier having depending flanges received in said forwardly extending channel shaped portion and pivotally connected thereto, said carrier being connected to said barrel and adapted to support the same with its breech end positioned in operative relationship with said breech block.

HERBERT E. MILLS.
